UNITED STATES PATENT OFFICE

140,688

DESIGN FOR A DOLL OR SIMILAR ARTICLE

Joseph C. Grant, Glendale, and Richard M.
Huemer, North Hollywood, Calif.

Application January 8, 1945, Serial No. 117,334

Term of patent 7 years

(Cl. D34—2)

To all whom it may concern:

Be it known that we, Joseph C. Grant and Richard M. Huemer, both citizens of the United States, and residents of Glendale and North Hollywood, respectively, in the county of Los Angeles, State of California, have jointly invented a new, original, and ornamental Design for a Doll or Similar Article, of which the following is a specification, reference being had to the accompanying drawing, forming a part thereof.

We claim:

The ornamental design for a doll or similar article, as shown.

JOSEPH C. GRANT.
RICHARD M. HUEMER.
